(57) **CLAIM**

The ornamental design for a rope play device, as shown and described.

DESCRIPTION

FIG. 1 is a top view of our rope play device;

FIG. 2 is a perspective view from below;

FIG. 3 is a first perspective view from above;

FIG. 4 is a second perspective view from above;

FIG. 5 is a third perspective view from above;

FIG. 6 is a fourth perspective view from above; and,

FIG. 7 is a side view.
